CLAIM

The ornamental design for vehicle decor, as shown and described.

DESCRIPTION

FIG. 1 is a perspective view of a vehicle decor showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In drawing FIG. 3, the broken lines depict bolt holes and form no part of the claimed design.
